Primary Examiner—Susan J. Lucas*Assistant Examiner*—Cynthia E. Ramirez*Attorney, Agent, or Firm*—Thompson Hine & Flory LLP[57] **CLAIM**

The ornamental design for a utility cart frame, as shown and described.

DESCRIPTION

FIG. 1 is a perspective front view thereof, taken from above and the right, and including utility cart wheels shown in phantom;

FIG. 2 is a perspective front view of a utility cart frame embodying my new design taken from above and the right; FIG. 3 is a right side elevational view thereof, and including utility cart wheels shown in phantom;

FIG. 4 is a right side elevational view thereof, the left side elevational view being a mirror image;

FIG. 5 is a front elevational view thereof;

FIG. 6 is a rear elevational view thereof;

FIG. 7 is a top plan view thereof; and,

FIG. 8 is a bottom plan view thereof.

The broken line showing of the wheels in the disclosure is for illustrative purposes only and forms no part of the claimed design.
